UNITED STATES PATENT OFFICE.

JAMES H. BOYE, OF CHICAGO, ILLINOIS, ASSIGNOR TO JAMES H. BOYE MANUFACTURING COMPANY, OF CHICAGO, ILLINOIS, A CORPORATION OF ILLINOIS.

DESIGN FOR AN END BRACKET FOR CURTAIN-RODS.

52,555.

Specification for Design.

Patented Oct. 15, 1918.

Application filed May 10, 1917. Serial No. 167,842. Term of patent 14 years.

To all whom it may concern:

Be it known that I, JAMES H. BOYE, a citizen of the United States, residing at Chicago, in the county of Cook and State of Illinois, have invented a new, original, and ornamental Design for End Brackets for Curtain-Rods, of which the following is a specification, reference being had to the accompanying drawing, forming part thereof, and in which—

Figure 1 is a plan view; Fig. 2 is an end elevation; and Fig. 3 is a perspective view of an end bracket for curtain rods, showing my new design.

I claim:

The ornamental design for an end bracket for curtain rods, as shown.

JAMES H. BOYE.
